To all whom it may concern:

Be it known that I, WILLIAM B. TABOR, of the city of Alhambra, Madison county, State of Illinois, have invented a new and original Design for Kitchen-Cabinets, of which the following is a full, clear, and exact description, reference being had to the accompanying drawing, forming a part thereof.

The figure is a perspective view of a kitchen-cabinet embodying my design.

As shown in the drawing, the leading or material feature of my design consists of a rectangular body 1, having a flat top 2, on the front face of which body 1 appears a plurality of rectangular panels 3, the same being irregular in size. Extending upwardly from the rear side of the top 2 of the body 1 is a sup-

port 4, having a curved ornamental top 5, and projecting forwardly from this support 4 is a pair of horizontally-arranged shelves 6, 20 between the outer corners of which are the ornamented posts or pillars 7. Located between the shelves 6 is a rectangular body 8, the same being located midway between the ends of the shelves 6. 25
